UNITED STATES PATENT OFFICE.

JOHN J. CONWAY, OF BRIDGEPORT, CONNECTICUT, ASSIGNOR TO THE ACME SHEAR COMPANY, OF BRIDGEPORT, CONNECTICUT, A CORPORATION OF CONNECTICUT.

DESIGN FOR A DISPLAY-STAND FOR ARTICLES OF MANUFACTURE.

48,709.

Specification for Design.

Patented Mar. 14, 1916.

Application filed September 20, 1915. Serial No. 51,723. Term of patent 7 years.

To all whom it may concern:

Be it known that I, JOHN J. CONWAY, a citizen of the United States, residing at Bridgeport, county of Fairfield, State of Connecticut, have invented a new, original, and ornamental Design for a Display-Stand for Articles of Manufacture, of which the following is a specification, reference being had to the accompanying drawing, forming part thereof.

Figure 1 is a front elevation of a display stand showing my new design, and Fig. 2 is a side elevation corresponding therewith. What I claim as new and desire to patent is:—

The ornamental design for a display stand for articles of manufacture, substantially as shown.

In testimony whereof I affix my signature.
JOHN J. CONWAY.
